UNITED STATES PATENT OFFICE.

JOHN J. HOWARD, OF PITTSBURGH, PENNSYLVANIA, ASSIGNOR TO JAS. H. MATTHEWS & CO., OF PITTSBURGH, PENNSYLVANIA, A CORPORATION OF PENNSYLVANIA.

CHANGEABLE TYPE-BLOCKS.

1,039,131.

Specification of Letters Patent. Patented Sept. 24, 1912.

Application filed June 18, 1912. Serial No. 704,312.

To all whom it may concern:

Be it known that I, JOHN J. HOWARD, a citizen of the United States, and residing in the city of Pittsburgh, in the county of 5 Allegheny and State of Pennsylvania, have invented or discovered new and useful Improvements in Changeable Type-Blocks, of which the following is a specification.

My invention consists in new and useful 10 improvements in interchangeable type-blocks which are used for stenciling or stamping and for similar purposes. Such type-blocks are commonly made of rubber or other compressible material and are held 15 on the holder by the angular flanges of the latter engaging the lateral edges or base-flanges of the former. Owing to the viscosity of the ink used, the type tend to adhere to the surface being marked, frequently 20 pulling the type-blocks loose from the holder and causing much inconvenience and delay.

My object is to prevent this loosening of the type-blocks from the holder, and I accomplish the same by providing the lateral edges or base-flanges of the type-blocks with 25 grooves or troughs which, when the type adhere to the surface being marked, engage and interlock with the angular flanges of 30 the holder and prevent the loosening of the type-blocks from the holder.

In the accompanying drawings, Figure 1 is a perspective of a holder of the "rocker" type with my improved type-blocks mounted 35 thereon; Fig. 2 is a section of the same along the line II--II in Fig. 1, but showing the type-block bowed up as if adhering to the surface being printed; Fig. 3 is a perspective of one of my type-blocks, and Fig. 40 is a vertical, transverse, sectional view of my type-block unprovided with base-flanges.

The following is a detailed description of the drawings:

A represents a type-holder, which for the 45 sake of illustration is shown as a "rocker" holder, composed of face plate 1 provided at its end with rearwardly bent portions 2--2 between which is secured the wooden hand-grasp 3. It will be understood how- 50 ever, that my improved type-blocks may be advantageously used with any of the holders now in use. The holder A is provided along its lateral edges with metal flanges B--B,

composed of a vertical portion 4 and an inwardly extending, substantially horizontal, 55 portion 5.

C--C are the type-blocks having on their faces various letters, numbers or other features, as required. Said blocks are usually provided with base-flanges 6--6 60 which are seated under the lateral flanges B--B of the holder to retain the type-blocks on the holder. It is evident that with no grooves or troughs provided in the base-flanges of the type-blocks, when the said 65 blocks are bowed outwardly, as shown in Fig. 2, by the adherence of the type to the surface being printed, said flanges would be readily drawn from beneath the flanges B--B, thus releasing the type-blocks from 70 the holder. I provide, however, the base-flanges 6--6 with grooves or troughs 7--7 75 in their upper surfaces which, when the type-blocks are bowed upwardly as shown in Fig. 2, engage or interlock with the flanges B--B of the holder and render the forcible withdrawal of said base-flanges from beneath said holder-flanges impossible.

In case the type-blocks are unprovided 80 with base-flanges, as in Fig. 4, and the bases of the blocks are engaged by the holder-flanges, the grooves or troughs 7--7 may be formed in the top-faces of the type-block adjacent to its lateral edges. 85

The type-blocks are mounted on the holder either by sliding the former under the flanges B--B at one end of the holder or pinching the blocks so as to compress their bases sufficiently to permit the insertion of their base-flanges or lateral edges under said flanges B--B. 90

What I desire to claim is:—

1. The combination with a holder, provided with retaining-flanges extending along 95 the longitudinal edges thereof, of removable type-blocks disposed in said holder and having, in their upper faces, grooves extending parallel and adjacent to said flanges, said flanges being normally out of engagement 100 with said grooves, but engaging the same when said type-blocks are bowed upward.

2. The combination with a holder, provided with retaining-flanges extending along the longitudinal edges thereof, of removable 105 type-blocks disposed in said holder and hav-

ing lateral base-flanges disposed under said retaining-flanges, and provided, in their upper faces, with grooves extending parallel and adjacent to said retaining-flanges, said 5 retaining-flanges being normally out of engagement with said grooves, but engaging the same when said type-blocks are bowed upward.

Signed at Pittsburgh, Penna., this 13th day of June 1912.

JOHN J. HOWARD
